Des. 222,183
Patented Oct. 5, 1971

222,183

BOAT HULL

Peter A. Milne, Chichester, England, assignor to
Richmond Marine Limited, London, England

Filed Mar. 30, 1970, Ser. No. 22,095

Claims priority, application Great Britain Dec. 11, 1969

Term of patent 14 years

Int. Cl. D12—06

U.S. Cl. D71—1

FIG.4

FIG.5

FIG.6

FIG.7

FIG.8

Fig. 9

Fig. 10

FIG. 1 is a side view of a boat hull embodying my new design;

FIG. 2 is an upper plan view thereof;

FIG. 3 is a lower plan view thereof;

FIG. 4 is a longitudinal sectional view thereof taken on the line 4—4 of FIG. 2;

FIG. 5 is a cross sectional view thereof taken on the line 5—5 of FIG. 1;

FIG. 6 is a cross sectional view thereof taken on the line 6—6 of FIG. 1;

FIG. 7 is a cross sectional view thereof taken on the line 7—7 of FIG. 1;

FIG. 8 is a cross sectional view thereof taken on the line 8—8 of FIG. 1;

FIG. 9 is a front end view thereof; and

FIG. 10 is a rear end view thereof.

I claim:

The ornamental design for a boat hull, substantially as shown.
